UNITED STATES PATENT AND TRADEMARK OFFICE

Certificate

Patent No. D. 283,844

Patented May 20, 1986

On petition requesting issuance of a certificate for correction of inventorship pursuant to 35 USC 256, it has been found that the above identified patent, through error and without any deceptive intent, improperly sets forth the inventorship. Accordingly, it is hereby certified that the correct inventorship of this patent is Michel H. Saad, Herbert Wunder, William M. Saad, and Patrick E. Saad.

Signed and Sealed this 31st Day of March, 1987.

BRADLEY R. GARRIS,
*Office of the Deputy Assistant
Commissioner for Patents.*
